UNITED STATES PATENT OFFICE.

BARZILLAI PULLEN, OF PHILADELPHIA, PENNSYLVANIA

AUTOMATIC GAS CUT-OFF.

1,168,415.

Specification of Letters Patent. Patented Jan. 18, 1916.

Application filed April 27, 1915. Serial No. 24,365.

To all whom it may concern:

Be it known that I, BARZILLAI PULLEN, a citizen of the United States, residing at Philadelphia, in the county of Philadelphia and State of Pennsylvania, have invented new and useful Improvements in Automatic Gas Cut-Offs, of which the following is a specification.

My invention relates to a new and improved automatic cut-off valve for use in connection with gas light burners or systems where slot meters are employed.

The object of the invention is to provide a valve which will automatically close when the flow of gas is cut-off and the gas pressure leaves the feed pipes, thus preventing subsequent leakage through unlighted burners and danger from asphyxiations or explosions.

20 A further object of the invention is to provide an automatically closing valve which, after closing, will be held tightly to its seat, any renewed pressure serving to close it more firmly against its seat, so as 25 to render it necessary to manually open the valve in order to reserve the flow of gas to the burners.

30 A still further object of the invention is to provide a valve which is simple of construction, reliable and efficient in action, and which will remain open as long as there is pressure in the pipe between the meter and stop cock, but which will close immediately upon the cut-off of the pressure between the 35 meter and the stop cock and will remain closed until manually opened for the resumption of the gas supply.

40 The invention consists of the features of construction, combination and arrangement 45 of parts herein fully described and claimed, reference being had to the accompanying drawing in which:—

Figure 1 is a longitudinal section through an automatic gas cut-off embodying my invention, showing the valve in closed position and the valve casing interposed between the sections of a gas feed pipe. Fig. 50 55 2 is a similar view showing the disk in raised position for the flow of gas through the by-pass.

Referring to the drawing, 1 designates a valve casing, having inlet and outlet ends 2 and 3 which are internally threaded, as at 4 and 5, respectively, to receive the threaded 55 ends of the sections of a gas feed pipe (not shown) between which such valve casing is

interposed. The casing is arranged in practice at a point in the line of the pipe between the slot meter and a controlling cock, which may be the stop cock of a furnace, 60 so as to be governed by the presence or absence of gas pressure within the pipe. The casing is formed with a valve chamber 8 which also serves as a pressure chamber, which valve chamber is provided at its bottom portion with a tapered valve seat 9 and is normally open at its top to permit of the application and removal of the valve, and is closed by a cap or plug 10. The end 2 of the valve casing is provided with a gas intake passage 11 which communicates with the lower portion of the chamber 8 above the plane of the valve seat through a restricted intake port 12, while the outlet end 3 of the valve casing is provided with an outlet passage 13 communicating with the bottom of the chamber 8 through a restricted outlet port 14' opening through the bottom of the valve seat 9. A valve 15 is arranged for movement within the chamber 8 and comprises a tapered disk adapted to close snugly against the seat 9, and of such thickness that when in closed position its upper surface lies below the plane of the port 12. The valve is carried by a stem 16, the upper 85 end of which moves in a guide socket or recess 17 in the plug 10 and the lower end of which moves in a guide passage or chamber 18 formed in the lower central portion of the valve casing, whereby the valve is accurately guided and centered in its movements. The valve is of proper weight to drop or close by gravity when not held supported by gas pressure, as hereinafter described.

95 As shown, the restricted portion 14' of the outlet passage 13 of the valve casing is closed against direct communication with the valve chamber 8 but communicates with an enlarged portion 18' of the guide passage 18, between the upper end of said guide passage and the threaded recess 19, which chamber or enlargement 18' is connected at its lower end with the valve chamber 8 through the medium of a restricted port or 100 passage 25 opening at its lower end into the passage 18' adjacent to its point of intersection with the recess 19 and at its upper end through the valve seat 9. Fitted in the recess 19 is an externally and internally 105 threaded screw plug 20', and fitted within said plug is a second screw plug 26 through

which passes a screw threaded adjusting stem 21' provided at its outer end with a button or finger piece 22'. Vertically movable in the passage 18' is a disk 27 interposed between said adjusting stem and the lower end of the valve stem. When the adjusting stem is elevated motion will be communicated through the disk to the valve 15 to raise the latter in the chamber 8, whereby 5 the disk is also raised in the chamber 18', a constricted passage 25 being thus brought into open communication with the passage 8 and inlet 2. The disk 27, which performs the function of a secondary controlling 10 valve, is of a thickness somewhat less than the depth of the contracted portion 14' of the passage 13, and hence when the valve is elevated and said disk is in raised position a sufficient amount of gas may flow by way 15 of the passage 12, chamber 8, passage 25, chamber 18', the duct 14', and outlet passage 13' to the burner or burners to supply the latter, while at the same time the volume of constricted area of the passage 25 20 will serve to retain in the chamber 8 gas under pressure to hold the valve 15 elevated even in the event that the normal service pressure should be of a low degree and the active service pressure should fluctuate to 25 some considerable extent. Thus provision is made for holding the valve open for service action under the conditions mentioned where a valve which may be held open under a low service pressure is needed. 30

35 It will thus be evident that when the supply of gas is cut off the safety valve will

close automatically, and on the resumption of gas flow will continue to remain closed, and in fact will be held absolutely closed by the gas pressure, until it is manually opened. 40 All danger of explosions or asphyxiations of persons from the admission of gas into a house or apartment through open burners will thus be entirely obviated. It will be seen that a simple construction of valve for 45 this purpose is provided which is not liable to get out of order and which may be manufactured and sold at a comparatively low cost. 50

I claim:—

An automatic gas cut-off comprising a valve casing having a valve chamber, an inlet port communicating with the lower portion of the valve chamber, a guide passage communicating with said valve chamber through a by-pass, an outlet port communicating with said guide passage, a constricted passage between the valve chamber and guide passage, a self-closing valve in the valve chamber having a stem depending 60 into the guide passage, an outlet passage provided with a restricted inlet communicating with the guide passage, an adjusting member, and a valve disk loosely mounted in the guide passage between said restricted 65 passage and constricted end of the outlet passage, said disk being interposed between said adjusting device and the valve stem and being of less thickness than the depth of the said constricted inlet of the outlet passage. 70

In testimony whereof I affix my signature.
BARZILLAI PULLEN.
